FLUID HEATING APPARATUS

Reginald B. Mildon, Lansdowne, Pa., assignor to Westinghouse Electric & Manufacturing Company, East Pittsburgh, Pa., a corporation of Pennsylvania

Application June 4, 1936, Serial No. 83,423

11 Claims. (CL. 122—30)

My invention relates to fluid heaters of the type disclosed in the copending application of R. A. Foresman, Serial No. 658,334, filed February 24, 1933, and it has for an object to provide improved apparatus of this kind.

A further object of my invention is to provide an improved fluid heater of the type having a rotatable annular grate with a magazine arranged above the grate to feed the fuel gravitationally to the grate and in which fluid heater the air for combustion is preheated before being supplied to the grate.

A still further object of my invention is to provide a fluid heater of the foregoing character wherein the walls of the magazine disposed above the grate are air-cooled so as to insure against objectionable heating of the fuel contained in the magazine.

These and other objects are effected by my invention, as will be apparent from the following description and claims taken in connection with the accompanying drawings, in which:

Fig. 1 is a plan view of my improved fluid heater;

Fig. 2 is a sectional view taken along the line II—II of Fig. 3;

Fig. 3 is a vertical section taken along the line III—III of Fig. 2;

Fig. 4 is a sectional view taken along the line IV—IV of Fig. 3;

Fig. 5 is a section taken along the line V—V of Fig. 1;

Fig. 6 is a sectional view of a portion of the apparatus shown in Fig. 5 and is taken along the line VI—VI thereof;

Fig. 7 is a front elevation of the heater; and,

Fig. 8 is a fragmentary section taken along the line VIII—VIII of Fig. 2.

Referring now to the various figures of the drawings, fluid, such as, for example, water is heated in a structure 9 having outer spaced walls 10 and 11 and an inner column 12 forming, respectively, water spaces 13 and 14. A hollow baffle member 15 connects the inner column 12 and the wall 11 and provides a communicating space 16 between the water spaces 13 and 14. A conduit 17 admits water to the space 13 and the heated water or vapor is discharged through conduits 18 and 19 located near the top of the heater.

The portion of the wall 19 adjacent the water space 13 is arcuate in shape as best shown in Fig. 2, the ends of the arcuate portion having radial walls 21 and 22 secured thereto. Spaced

5 sponding walls 21' and 22'. The radial walls are joined at their inner ends as shown at 23 and 23' and divide the circular heating structure into arcuate chambers 24 and 25; the former comprising a combustion space and the latter a fuel 10 magazine. The portion 26 of the wall 10 which defines the outer wall of the magazine 25 may be of a single thickness of material and need not be cooled as it is not subjected to the high 15 temperatures prevailing in the combustion chamber.

As the walls 21 and 22 of the fuel magazine 25 are subjected to the high temperature prevailing in the combustion chamber, it is advisable that they be cooled and some means such as, 15 for example, a blower 30 is provided for circulating air between the walls 21 and 21' and the walls 22 and 22' respectively. Further reference to the cooling of the walls 21 and 22 and to the translation of the air by the blower 30 will be 20 made hereinafter.

The structure 9 is preferably supported on a base 26 having outer and inner wall members 27 and 28. An annular grate structure 29 is rotatably supported by the base 26 as best shown in 25 Fig. 3. The grate 29 defines the bottom of the combustion chamber 24 and the fuel magazine 25. Coal from the magazine 25 is, therefore, fed by gravity to the grate. Rotation of the grate 29 may be effected in any suitable manner as, by 30 a pawl and ratchet mechanism shown at 33 in Fig. 6. The latter mechanism may include a pawl 34 carried by a shaft 35 which is oscillated in any suitable manner. The pawl 34 engages a ratchet 36 formed on the underside of the grate 35 structure 29, so that as the shaft 35 is oscillated, the pawl 34 advances the grate 29 step by step and in clockwise direction, as viewed in Fig. 2. The shaft 35 is operated periodically in response to demands for heat, all as is well understood in 40 the automatic heating art. Preferably, the blower 30 and the shaft 35 are simultaneously operated so that air is translated to the grate 29 by the blower 30 only during periods when the grate is operated.

As shown in Fig. 4, the base 26 is divided by radial walls 37, 38, and 39 forming a windbox 41 and an ash receiving chamber 42. The walls 31, 38, and 39 extend from the bottom of the base 26 to the top thereof and provide a further support for the grate 29. An additional wall 43 may extend radially of the windbox 41 for supporting the grate 29 and includes an opening 44 for passage of combustion air. The upper edges of the walls 37, 38, 39, and 43 are flanged, as shown at 55

45 in Fig. 6, for providing suitable bearing surfaces for the grate and for sealing the windbox 41 and chamber 42. This form of seal is well known in the art and is described in the aforementioned application of R. A. Foresman.

5 The ash receiving chamber 42 is provided with a receptacle 47 for ash discharged from the grate 29. Further reference to the discharge of ash will be made hereinafter. A hinged door 48 is provided for access to the receptacle 47.

10 As shown in Fig. 3, the wall members 21 and 21' of the magazine 25 extend downwardly toward the base 26 and terminate adjacent the upper surface of the grate. They are closed at their 15 lower ends, as shown at 50 except for an opening 51 located at the outer end thereof and communicating with the windbox 41. In order to feed fuel from the magazine to the combustion chamber, a suitable opening or passage 53 extends 20 through the walls 21 and 21'. As the bottom of the magazine is wider than the grate 29, sloping plates 54 and 55 are provided for directing the fuel onto the grate 29 as best shown in Figs. 2 and 3.

25 An ash discharge opening 56 is provided in the outer walls 10 and 11 adjacent the magazine wall 22. The ash is deflected outwardly of the grate 29 by a plate 57 secured to the structure 9 in any suitable manner. As shown, the plate 57 is secured to the inner column 12 and to the wall 11, this plate 57 being preferably arranged at a tangent to the grate for facilitating the radial movement of ash as the grate rotates. It will be apparent that ash deflected from the grate falls 30 over the periphery of the grate into the container 47.

35 The structure 9 may include a top wall 58 having an outlet 59 for products of combustion, as shown in Fig. 1. The outlet 59 is connected to a suitable flue, not shown, for the discharge of the products of combustion. An arch structure 61 may be disposed in the combustion chamber 24, as best shown in Figs. 1 and 3, which arch structure extends from the wall 21 to the line 61 (Fig. 45 1) so as to lengthen the path of gas travel from the grate to the outlet 59.

40 Fuel is admitted to the magazine 25 in any suitable manner as through a door opening 62 formed in the wall 26. In order to further protect the walls 21 and 22 from the heat of combustion, they may be lined with suitable refractory as shown at 65 and 66, respectively.

45 In order to operate the foregoing heater, the magazine is filled with coal and the shaft 35 is oscillated. Oscillation of the shaft 35 actuates the pawl and ratchet mechanism 33 which rotates the grate 29, whereupon fuel from the magazine passes through the opening 53 into the combustion chamber. The fuel is levelled by the upper 50 edge of the opening 53 so that the bed of fuel is maintained at a predetermined uniform thickness as it enters the chamber 24. Ignition is effected adjacent the wall 21 and the fuel is progressively burned as it slowly rotates with the grate through 55 the combustion chamber 24, combustion being completed at some point between the wall 21 and the plate 57 dependent upon the load on the boiler. The refuse is deflected outwardly by the plate 57 as the grate 29 advances therebeneath, and 60 the refuse drops over the outer edge of the grate into the receptacle 47.

65 Air for supporting combustion is drawn from the surrounding atmosphere through the inlet 30' of the blower 30 and is discharged between 70 the walls 22 and 22' and thence the walls 21 and

21'. In its passage between these walls, the air is preheated. The heated air travels downwardly between the walls 21 and 21' and thence through the opening 51 into the windbox 41. The walls 21 and 22 are thereby effectively cooled and the combustion supporting air is preheated so that the combustion efficiency of the furnace and its reliability are improved.

75 During periods when there is no demand for additional heat and the shaft and the blower are inactive, the supply of air to the grate is substantially reduced. At this time, the outlet 59 being connected to a suitable flue, there is a circulation of air by natural draft which is sufficient to cool the walls 21 and 22 and to maintain combustion.

80 From the foregoing, it will be apparent that I have provided an improved fluid heater of the annular grate type wherein the fuel magazine walls are effectively cooled and the combustion supporting air is preheated, thereby increasing the efficiency of the fluid heater.

85 While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

90 What I claim is:

95 1. In fluid heating apparatus, the combination of a rotatable grate, an outer wall structure disposed above the grate and embodying a space for fluid to be heated, a pair of wall structures joined at their inner ends adjacent the central portion of the grate and extending transversely of the grate, said transversely extending walls and a portion of the outer wall defining a magazine for the gravitational feeding of fuel to the 40 grate and one or more of the transversely extending wall structures having a passage formed therein, and means for admitting air to said passage.

100 2. In fluid heating apparatus, the combination of a rotatable grate, an outer wall structure disposed above the grate and embodying a space for fluid to be heated, a pair of wall structures joined at their inner ends adjacent the central portion of the grate and extending transversely of the 50 grate, said transversely extending walls and a portion of the outer wall defining a magazine for the gravitational feeding of fuel to the grate and one or more of the transversely extending wall structures having a passage formed therein, means for admitting air to said passage, and means for conducting the air from the passage to the combustion chamber for supporting combustion.

105 3. In fluid heating apparatus, the combination of a rotatable grate, an outer wall structure disposed above the grate and embodying a space for fluid to be heated, a pair of wall structures joined at their inner ends adjacent the central portion of the grate and extending transversely 65 of the grate, said transversely extending walls and a portion of the outer wall defining a magazine for the gravitational feeding of fuel to the grate and one or more of the transversely extending wall structures having a passage formed 70 therein, means for admitting air to said passage, and means for conducting air from the passage in said transversely extending wall structures to the underside of the grate.

110 4. In fluid heating apparatus, the combina-

tion of a rotatable annular grate, an outer wall having spaces therein for the medium to be heated and arranged above the perimeter of the grate, first and second circumferentially spaced walls extending inwardly from the outer wall and joined at their inner ends for defining a fuel magazine above an arcuate portion of the grate, the remaining portion of the grate defining a combustion chamber, said first circumferentially spaced wall having a portion thereof spaced above the grate and defining, therewith, a fuel discharge orifice, and said second circumferentially spaced wall terminating adjacent to the grate, a passage formed in said circumferentially spaced walls for the circulation of air therethrough, and means for admitting air to the passages in the circumferentially spaced walls for cooling the same.

5. The combination as claimed in claim 4 wherein at least one of said circumferentially spaced walls includes a layer of refractory on the side thereof adjacent the combustion chamber.

6. In fluid heating apparatus, the combination of a rotatable annular grate, a structure arranged above the grate and having spaces formed therein for fluid to be heated, said structure defining a combustion chamber above an arcuate portion of the grate, a magazine for fuel disposed above a second arcuate portion of the grate and including first and second walls spaced circumferentially with respect to the grate and joined at their inner ends, said first and second magazine walls having passages formed therein, said first magazine wall being spaced above the grate for defining, therewith, a fuel discharge opening, means for rotating the grate, means for admitting fuel to the magazine so that it passes through said opening as the grate is rotated, means for passing air through the passages of the magazine 40 walls for cooling the same and means for conveying the heated air from said passages to the grate.

7. In fluid heating apparatus, the combination of a rotatable annular grate, a base member for supporting the grate and defining a windbox beneath an arcuate portion of the grate, a boiler structure carried by the base member and including a wall disposed above the periphery of the grate, said wall having a space therein for water to be heated and defining a combustion chamber above said arcuate portion of the grate, a magazine for fuel disposed above a second arcuate portion of the grate and including first and second walls joined at their inner ends and extending transversely of the grate, said first and second magazine walls having a passage formed therein, said first magazine wall having its bottom portion spaced above the grate for defining therewith a fuel discharge orifice, means disposed adjacent the second magazine wall for deflecting ash radially from the grate, means for rotating the grate, means for admitting fuel to the magazine for passage through the orifice as the grate is rotated, and means for translating air for supporting combustion through the passage of the magazine walls and thence to said windbox, whereby the magazine walls are cooled and the combustion supporting air is heated prior to its passage through the grate.

70 8. In fluid heating apparatus, the combination

of a rotatable annular grate, a wall arranged above a portion of the periphery of the grate and having a space formed therein for fluid to be heated, said wall defining a combustion chamber above an arcuate portion of the grate, a magazine for fuel disposed adjacent a second portion of the periphery of the grate and having at least a portion thereof above a second arcuate portion of the grate, said magazine including first and second circumferentially spaced walls extending transversely of the grate and joined at their inner ends, said magazine including an outer wall connecting the outer ends of the circumferentially spaced walls, at least a portion of said magazine walls having a jacket formed therein, said first magazine wall having a portion thereof spaced vertically from the grate for defining a fuel discharge orifice, means for rotating the grate, means for admitting fuel to the magazine to be passed through said orifice into the combustion chamber as the grate is rotated and means for translating air for combustion through said jacket and thence to a portion of the underside of the grate, whereby the magazine walls are cooled and the combustion supporting air is heated prior to its passage through the grate.

9. In fluid heating apparatus, the combination of a rotatable circular grate, a fluid heating structure disposed above the grate and having wall members defining a combustion chamber above a segment of the grate, said wall members having spaces therein for fluid to be heated and a magazine for fuel elevated with respect to a second segment of the grate for delivering fuel by gravity thereto, said magazine including circumferentially spaced means extending transversely of the grate and having a passage formed therein for the circulation of air.

10. In fluid heating apparatus, the combination of a rotatable circular grate, a fluid heating structure disposed above the grate and having wall members defining a combustion chamber above a segment of the grate, said wall members having spaces therein for fluid to be heated, a magazine for fuel elevated with respect to a second segment of the grate for delivering fuel by gravity thereto, said magazine including circumferentially spaced means extending transversely of the grate and having a passage formed therein, and means for translating air through said passage to the grate for supporting combustion thereon.

11. In fluid heating apparatus, the combination of a rotatable circular grate, a fluid heating structure disposed above the grate and having wall members defining a combustion chamber above a segment of the grate, said wall members having spaces therein for fluid to be heated, a magazine for fuel elevated with respect to a second segment of the grate for delivering fuel by gravity thereto, said magazine including first and second means extending transversely of the grate and having an air passage formed therein, one of said transversely extending means being spaced above the grate for defining an opening for the passage of fuel from the magazine to the combustion chamber and means for admitting air to said air passage.

REGINALD B. MILDON. 70
